UNITED STATES PATENT OFFICE.

WILLIAM C. HOMAN, OF MERIDEN, CONNECTICUT, ASSIGNOR TO EDWARD MILLER & COMPANY, OF SAME PLACE.

GAS-COCK.

SPECIFICATION forming part of Letters Patent No. 398,616, dated February 26, 1889.

Application filed November 5, 1888. Serial No. 289,959. (No model.)

To all whom it may concern:

Be it known that I, WILLIAM C. HOMAN, of Meriden, in the county of New Haven and State of Connecticut, have invented a new Improvement in Gas-Cocks; and I do hereby declare the following, when taken in connection with accompanying drawings and the letters of reference marked thereon, to be a full, clear, and exact description of the same, and which said drawings constitute part of this specification, and represent, in—

Figure 1, a front view of the cock complete; Fig. 2, a side view of the same; Fig. 3, an inlet end view; Fig. 4, a vertical central section 15 cutting through the projection and showing the plug in side view; Fig. 5, a vertical central section of the shell with the plug and sleeve removed; Fig. 6, a modification.

This invention relates to an improvement 20 in that class of cocks for gas-burners which are designed to permit a slight escape of gas, so as to support a very small flame, but which are adapted to be turned so as to admit a full supply of gas, or to cut off the full supply 25 down to the very slight flame without the possibility of entirely extinguishing the flame, and so that the full supply may be instantly admitted or cut off with a certainty that the flame will not be extinguished in the act of 30 cutting off; and it consists in the construction, as hereinafter described, and more particularly recited in the claims.

A represents the body or shell of the cock, which is constructed at one end with a male 35 or female screw corresponding to the tip to which the cock is to be applied. (Here represented as a female screw, B.) The other end is also provided with a screw, to which the burner may be applied. (Here represented as 40 a male screw, C.)

From one side of the shell a tubular projection, D, is formed cylindrical upon its outer surface, as seen in Fig. 5. In the shell is a chamber, E, in line with and which opens 45 into the interior of the projection D; but this chamber E is of smaller area than the transverse area of the interior of the projection D, and so as to form a seat, a, between the chamber E and the interior of the projection D.

50 From the inlet end of the shell a passage, b,

opens to the chamber E, and from the interior of the projection D a passage, d, leads to the exit of the shell. Into the tubular projection D a cylindrical plug, F, is closely fitted, but so as to be easily rotated therein. The 55 end of this plug normally rests against the seat a, between the interior of the projection D and the chamber E, and so as to cut off communication between the chamber E and the outlet of the shell, except as to a slight 60 escape-passage, e, from the chamber E directly into the outlet-passage f. This escape-passage e is what is commonly called a "thief." When the plug F rests against the seat a, all communication between the 65 inlet-passage and the outlet-passage is cut off, except as to the thief e; but if the plug be withdrawn from its seat then passage is opened from the inlet to the outlet for a full escape. To thus withdraw the plug 70 F and open the passage, a sleeve, G, is fitted to the exterior cylindrical surface of the projection D. This sleeve is of cup shape, closed at its outer end, and to this closed end the plug is secured, as seen in Fig. 4. The projection, the sleeve, and the plug, all being concentric, permit the rotation of the sleeve and plug around and in the projection D. The plug, however, fits so closely within the projection D as to prevent the escape of gas 80 around the plug. This sleeve G is constructed with a cam-shaped slot, g, (see Figs. 2 and 3,) and on the exterior surface of the sleeve G is a radially-projecting stud, h, corresponding to the slot g. If the sleeve G be 85 rotated in one direction, the slot g operates upon the stationary stud h as a cam, and withdraws the sleeve from the projection, and with it the plug F, as represented in broken lines, Fig. 4, and so as to open full 90 communication for the escape of gas to the burner. Turned in the opposite direction, the slot g operates upon the stud h to force the plug to its seat a, and so as to cut off the escape of gas, except as to the thief, as before 95 described.

As a convenient means for rotating the sleeve G, it is provided with two radially-projecting arms, H I, and for convenience chains or cords are attached thereto, as seen in Fig. 100

1, so that a pull upon one arm will turn the sleeve in one direction and withdraw the plug, or the pull upon the other arm will turn the sleeve in the opposite direction and force 5 the plug to its seat.

For convenience of applying the sleeve G to the projection D, the slot *g* is constructed with a longitudinal opening, *i*, to the inner edge of the sleeve, so that when the sleeve is 10 set onto the projection, and the opening *i* is in line with the stud, it will pass on to its proper position and bring the stud *h* into line with the cam-shaped portion of the slot.

It will be understood that ordinarily the 15 usual gas-cock is employed, my improved cock being arranged directly at the burner and between the burner and the usual full cut-off cock, and so that my improved cock may be employed as a regulator for the 20 burner as well as to cut off the supply down to the thief, or admit the full supply by simply turning the sleeve as occasion may require, and this turning may be made without danger of extinguishing the flame or of admitting 25 too great a supply, the sleeve being stopped in its rotation when the full supply is on, and also stopped when cut down to the thief by coming to its seat *a*.

The arms H I, projecting from the sleeve, 30 may be omitted from the sleeve and the sleeve turned directly by hand; but the arms are a convenience for rotating the sleeve.

While I prefer to impart the rotative and longitudinal movement to the plug F by means 35 of the surrounding sleeve, both for convenience and because the sleeve aids in packing the joint around the plug, the sleeve may be omitted, and the spiral or cam-shaped slot *g* formed directly in the plug, as seen in Fig. 6, 40 and the stud *h* extended into the said slot *g*, so that the same longitudinal movement will be imparted to the plug as that which I have described as produced by the sleeve G. I therefore do not wish to be understood as limiting 45 the invention to the employment of the sleeve G around the projection.

I claim—

1. The herein-described cock, consisting of 50 a shell constructed with an inlet at one end and an outlet at the opposite end, with an intermediate chamber, E, between said outlet and inlet, the outlet opening into the said

chamber E, the said shell constructed with a right-angular cylindrical projection, D, the interior of which is in line with and opens into 55 the said chamber E, but the transverse area of the interior of the projection greater than the transverse area of the chamber E, and so as to form a seat, *a*, between the said chamber and interior of the projection, the interior of the said projection also opening into the outlet-passage of the cock, the said seat constructed with a slight escape, *e*, into the outlet-passage, combined with a cylindrical plug, F, adapted to rotate in said projection 60 and to come to a bearing against the said seat *a*, and the said plug provided with a spiral or cam-shaped slot, and the said projection with a corresponding stud adapted to work in said cam-shaped slot, substantially as described, 65 and whereby under rotation of the said plug the said cam-shaped slot operating in connection with said stud will impart to the said plug a longitudinal movement from or to its seat, according to the direction in which the plug is 70 rotated.

2. The herein-described gas-cock, consisting of a shell having an inlet at one end and outlet at the opposite end, with an intermediate chamber, E, into which the outlet opens, the 80 shell constructed with a cylindrical tubular projection, D, the interior of said projection being in line with but of greater transverse area than the transverse area of the chamber E, and so as to form a seat, *a*, between the 85 said chamber E and the interior of the projection D, the interior of the said projection opening into the outlet-passage from the cock, combined with a rotative plug, F, in said chamber, constructed with or formed as a part 90 of a sleeve, G, concentric with and surrounding said cylindrical projection D, the sleeve constructed with a cam-shaped slot, *g*, and the projection provided with a corresponding stud, *h*, the seat between the chamber E and the interior of the projection D constructed with a slight escape, *e*, into the outlet-passage 95 of the cock, substantially as and for the purpose described.
